UNITED STATES PATENT OFFICE.

SIMAN MIYATA, OF WEST ORANGE, NEW JERSEY.

DESIGN FOR A PORTABLE DANCING-PAVILION.

SPECIFICATION forming part of Design No. 37,368, dated March 7, 1905.

Application filed January 20, 1905. Serial No. 242,003. Term of patent 7 years.

To all whom it may concern:

Be it known that I, SIMAN MIYATA, a citizen of the United States, residing at 191 Valley street, West Orange, county of Essex, and 5 State of New Jersey, have invented a new, original, and ornamental Design for a Portable Dancing-Pavilion, of which the following is a specification, reference being had to the accompanying drawings, forming part thereof.

10. The drawings show two views, of which— Figure 1 is a front elevation, and Fig. 2 a side elevation, of the portable dancing-pavilion.

What I claim as new, and desire to secure by Letters Patent, is—15 The ornamental design for a portable dancing-pavilion, as shown.

SIMAN MIYATA.
